UNITED STATES PATENT OFFICE.

WALTER S. LITTLE, OF BORDEAUX, WASHINGTON, ASSIGNOR OF ONE-HALF TO PHILIP G. MORRIS, OF BORDEAUX, WASHINGTON.

SAFETY-PIN.

1,188,956.

Specification of Letters Patent. Patented June 27, 1916.

Application filed December 21, 1915. Serial No. 68,073.

To all whom it may concern:

Be it known that I, WALTER S. LITTLE, a citizen of the United States, and a resident of Bordeaux, in the county of Thurston and State of Washington, have invented an improvement in Safety-Pins, of which the following is a specification.

This invention is an improvement in pins and has particular reference to a bracing device for the shanks or members of safety pins.

Heretofore, with safety pins commonly employed the movable member or shank containing the point is often bent and opened owing to undue strain thereon, sometimes occasioned by securing several thicknesses of material together, the opening of the pin often resulting in injury to the wearer.

The present invention is designed to overcome these objections by providing a brace slidably mounted upon one of the members of the safety pin and adapted to be detachably connected with the other member thereof whereby said members are effectively prevented from being bent intermediate their ends, thus avoiding detachment of the pin point from its shield or retainer.

Another object of the invention is the provision of a brace formed from a single sheet of material and having its body portion of substantially T-shaped formation, the transverse or cross piece thereof being provided with sleeves or bearings for receiving one of the members of the pin, the other end of the body portion being bent to provide a hook for detachable engagement with the other member of said pin.

A further object is to provide the body portion of the brace with bearings or sleeves on each side thereof whereby the bearing adjacent the shield of the pin will contact the same, should the brace be inadvertently moved toward that end of the pin, and thus prevent the hook end of said brace from interfering with the operation of fastening and unfastening said pin.

A still further object of the invention is the provision of a device of this character which is extremely simple in construction, thus reducing the cost of manufacture to a minimum, durable, and effective in carrying out the purpose for which it is designed.

The inventive idea involved is capable of receiving a variety of mechanical expres-

sions, one of which, for the purpose of illustrating the invention, is shown in the accompanying drawing, in which—

Figure 1 is a side elevation of the safety pin showing the invention applied thereto. Fig. 2 is a similar view looking from the other side. Fig. 3 is a transverse section on the line 3—3 of Fig. 1. Fig. 4 is a detail perspective view of the bracing device. Fig. 5 is a rear elevation of the pin showing the device applied thereto.

Referring more particularly to the accompanying drawing, in which like reference characters indicate similar parts, the numeral 10 indicates the relatively stationary member of a safety pin of ordinary construction having the coil spring 11 at one end and the shield or retainer 12 at its other end adapted to receive the pointed end of the relatively movable member or shank 13 of said pin. It is, of course, understood that the invention may be applied to other forms of pins than that shown in the drawing.

The bracing device 14 is formed from a single sheet of material, preferably metal, and is cut into a substantially T-shaped formation as best illustrated in Fig. 4. The body portion, at one end, has the transverse or cross piece 15 which is slightly curved in order to fit about the member 10 of the pin. The extremities of the cross piece 15 are provided with oppositely disposed sleeves or bearings 16 which are adapted to receive the member 10 therein whereby the bracing device is pivoted to said member 10 and movable longitudinally thereof. The opposite end of the body portion 14 has its extremity bent to provide a hook portion 17 which receives the relatively movable member 13 of the pin and detachably engages the same when the point thereof is shielded in the retainer 12. It will thus be seen that when the bracing device is in the position shown in Figs. 1 and 2 any tendency of the member 13 to bend outwardly intermediate its ends will be prevented, thus avoiding the accidental displacement of the pin point and possible subsequent injury to the wearer.

It will also be apparent that the brace may be moved longitudinally of the members 10 and 13 if desired but that the bearing 16 adjacent the shield 12 will limit the movement of the brace toward said shield and thus prevent the hook portion 17 from coming in contact with the

same and interfering with the opening of the pin.

What is claimed is:

5 A bracing device for safety pins of substantially T-shape and formed from a single sheet of material comprising a relatively narrow strip extending transversely of and between the members of the pin and having a hook at one end for engagement with one 10 of said pin members, the width of said hook being comparatively small relative to the length of said pin members, the other end of said narrow strip having lateral oppositely disposed extensions, the extremities of

which are bent at right angles thereto and 15 substantially parallel to said narrow strip, said extremities being bent to provide spaced bearings for receiving the member of the pin opposite that with which the hook engages whereby the device is pivoted 20 thereto, said device being movable longitudinally of said pin members for a distance exceeding the width of the device.
